OF OHIO

HAND-HOLE PLATE

Application filed May 3, 1927. Serial No. 188,553.

This invention relates to hand-hole plates for use in connection with boilers or tanks. The primary object of the same being to provide means of simplified construction whereby hand-hole openings in the shell or wrapper sheet of the boiler or tank may be securely closed and maintained so in steam, gas or water tight manner and yet which permits of the hole being readily opened and entirely cleared when desired.

A further object is to provide closure means for hand-hole openings which is featured by means of improved nature for effecting an extremely tight seal and without subjecting the shell or wrapper sheet to strain or distortion.

Still further the invention aims to provide simplified assemblage means for the cover plate and its associated parts which enables the same to be quickly and easily installed or removed without the necessity of special skill or tools, which permits of an extremely tight and efficient seal being made, and which holds the plate locked in tight position with little likelihood of the same becoming loosened incident to jarring or vibratory action.

With these objects in view, together with others which will appear as the description proceeds, the invention consists in the novel construction, combination and arrangement of parts, all as will be described more fully hereinafter, illustrated in the drawing, and particularly pointed out in the claim.

Referring to the drawing:

35 Fig. 1 is a fragmentary top plan view of the improved hand-hole cover plate construction, and

Fig. 2 is a sectional view taken transversely through the assemblage and through a 40 part of the shell with which it is associated.

The boiler head, casing or shell is represented generally at 3, and is provided with the usual circular hand-hole opening to permit of access being had to the interior at required times. The edge of this opening, in the present instance, is bevelled outwardly as indicated at 4, providing an annular inclined seat co-extensive with the opening.

The hand-hole plate is indicated at 5, and 50 is of substantially disc-shape with its edges

cut away at opposite sides, as represented at 6, to a size substantially equal to the diameter of the opening. This permits of the plate passing through the opening when tilted slightly, as will be readily understood. The 55 remaining edges of the plate are provided with an outwardly projecting flange 7 to overlie the inner face of the shell adjacent the opening therein, and the outer face of the plate is rounded or bevelled as at 8 in a direction substantially opposite to the bevel 4 of the opening.

Associated with the plate thus formed is a cap 9 of substantially disc-shape and having an annular inturned flange 10 with its edges 65 bevelled as shown to fit between the bevel of the shell opening and the adjacent rounded or bevelled portion of the hand-hole plate. The diameter of the cap is such that the extremity of the flange portion 10 thereof overlies the juncture between the hand-hole opening and the plate 5. A gasket, either metallic or non-metallic, indicated at 11 is disposed in the space or pocket between the boiler opening and the hand-hole plate, and if preferred this gasket may be of one piece so as to extend entirely around the opening. The gasket may be of circular cross section or angular as desired, and as before stated, may be of metallic or non-metallic formation. This 70 gasket lies directly beneath the edge of the in-turned flange 10 of the cap so as to be engaged directly thereby when the cap is properly placed over the hand-hole plate.

The plate 5 has projecting centrally and outwardly therefrom a bolt indicated at 12, the inner end of the same being headed as at 13 upon the inner side of the plate. The base portion of this bolt has an enlargement or shoulder indicated at 14, which portion is provided with one or more angular or flat faces as shown. The cap 9 is provided with an outwardly projecting boss 15 of a size and shape corresponding with the shoulder or enlargement 14 and of a size substantially equal to or a little larger than said enlargement. The cap 9 has an opening 16 centrally thereof through which the threaded end of the bolt 12 loosely passes, said opening, obviously, being disposed centrally of the boss 15. A nut 17 85 90 95 100

engages with the threads upon the outer end of the bolt.

In applying the hand-hole plate, the same is inserted in the opening by tilting action in the manner well understood, and when 5 properly engaged within the openings so that the flanges 7 thereof engage with the inner face of the shell adjacent the opening, the gasket 11 is applied to the groove formed between the opening and the plate. The cap is 10 then engaged over the bolt so that the in-turned flanges at the edges thereof rest upon the gasket 11. At the same time, the boss 15 will engage over the correspondingly shaped 15 shoulder or enlargement 14 of the bolt and any tendency of relative rotation between the bolt and the cap will thus be prevented. The nut 17 is then applied to the threads of the bolt and tightened. This tightening action 20 may be facilitated by applying a tool such as a wrench to the angular boss 15 to hold the same against rotation while the nut is being tightened. This tightening action causes the flange portions 10 of the cap to compress the 25 gasket within the channel or recess between the hand-hole opening and the plate 5, at the same time the said plate is caused to be drawn tight against the inner faces of the shell adjacent the opening. Tightening of the nut 30 therefore securely seals the joint between the plate and the shell, but the construction is such that no strains are transmitted to the shell itself.

The interlocking arrangement of the boss 35 and the enlargement of the bolt locks the parts securely in position and holds the same against relative movement without the application of force directed upon the nut. By applying a wrench to the boss of cap 9 in tightening or loosening the holding nut, the cap and plate are held against rotation, whereby applying and removing the device is greatly facilitated. In addition, the elimination of rotary movement of either the cap or hand-hole plate in these operations overcomes possibility of grinding or otherwise adversely 40 affecting the gasket. The construction of the hand-hole plate in its manner of assembly with the boiler or tank shell is such that fluid 45 pressure against the inner surface of the hand-hole plate does not increase compression upon the sealing ring or gasket, and any increase or decrease in fluid pressure, can, therefore, not alter the condition or effect of the 50 gasket or seat.

Having thus described our invention, we claim:—

In a device of the class described, a plate to close a boiler opening, a cap having an edge 55 to be brought substantially into contact with said plate, a boss on said cap projecting outwardly from the central portion of said cap, said boss presenting angularly disposed walls, a bolt carried by said plate and projecting centrally through said boss, an en-

largement on said bolt extending from said plate into said boss and having angularly disposed walls to coact with the walls of said boss, and a nut for the outer end of said bolt.

In testimony whereof we affix our signatures.

AMAZIAH J. MOSES.
FRANK H. WRIGHT.
